UNITED STATES PATENT OFFICE.

CHARLES F. RANDALL, OF BOSTON, MASSACHUSETTS, ASSIGNOR TO UNIVERSAL PATENTS COMPANY, OF WOONSOCKET, RHODE ISLAND, A CORPORATION OF RHODE ISLAND.

WOVEN BELT OR CARRIER.

1,287,098.

Specification of Letters Patent.

Patented Dec. 10, 1918.

Application filed September 30, 1918. Serial No. 256,185.

To all whom it may concern:

Be it known that I, CHARLES F. RANDALL, a citizen of the United States, residing at Boston, in the county of Suffolk, State of Massachusetts, have invented a certain new and useful Improvement in Woven Belts or Carriers, of which the following is a specification, reference being had therein to the accompanying drawings.

10 The invention has relation to woven belts or carriers on the order of those forming part of military equipment.

It is customary to suspend various articles of equipment from a belt or carrier by means of suspensory devices, usually so-called hangers, having hooks or the like engaging portions, usually of wire, which are engaged in eyelets or the like in connection with the belt or carrier. The general object 15 of the invention is to provide in connection with a belt or carrier convenient means to cover and shield the said engaging portions or hooks of the suspensory devices or hangers at the rear of the said eyelets or the like.

20 The invention consists, essentially, in a woven belt or carrier formed with a plurality of separable divisions, with the eyelets or the like which receive the suspensory devices or hanger-hooks of equipment provided in an intermediate division, and with covering or guard divisions at both sides of said intermediate division, adapted to cover and shield the suspensory device or hanger at both the front and the rear thereof.

25 An illustrative embodiment of the invention is shown in the drawings, in which latter,—

Figure 1 is an isometric of a portion of a pocketed belt or carrier containing said embodiment.

30 Fig. 2 is a view of the said belt or carrier in vertical cross-section between pockets thereof, illustrating the said embodiment.

Fig. 3 is a bottom view of a portion of the 35 said belt or carrier, also illustrating the invention.

Fig. 4 is a view showing a hanger separately.

The belt or carrier that is shown in part 40 in the drawings is a pocketed carrier of the same general description as that shown and described in U. S. Letters Patent for woven carrier, No. 1,210,377, granted under date of Dec. 26, 1916, upon the application of V. H. Jennings. As in the case of the belt or car-

rier of the said patent, it has the laterally-extending web 1 thereof, externally of the pockets divided in thickness alongside the bottoms of the said pockets, with the eyelets 5, 5, which receive the suspensory devices or hanger-hooks of other equipment set in one only of the said divisions. The bottoms of the pockets also are of bellows-bottom construction 1^a, 1^a, as in such patent. The general purpose in forming the belt or carrier with the said laterally-extending web divided in thickness as just mentioned is to afford increased movability and expandability of the lower portions of the front and side-walls of a pocket, enabling the 60 closed end of the pocket to conform more fully to the contour of the lower portion of the pocket-contents.

Patent No. 1,210,377 shows two divisions only, corresponding with the divisions 3 and 4 of the accompanying drawings, respectively constituting direct continuations of the front and back of the pocket, and movable therewith apart from each other, with the eyelets 5, 5, set in the rear division 3. 70 Consequently when the hooks 6, 6, of the hangers are engaged in such eyelets portions of the said hooks will be exposed at the back of division 3.

In its illustrated embodiment the present 85 invention is in a measure an improvement upon the pocketed carrier of the said patent.

The object of the present invention is shown in the drawings hereof as secured by means of a third division, *a*, which is woven 90 upon the belt or carrier so that it occupies a position behind division 3. This division is made separable from division 3 to an extent sufficient to permit the hangers, or other suspensory devices that may be employed, 95 to be hooked into the eyelets or unhooked therefrom. The division *a* may be in the form of a simple supplemental web joining along its top with another portion or portions of the belt or carrier. Preferably, 100 though not necessarily in all cases, the said supplemental web will be united or attached in its lower portion or across its width to the belt or carrier intermediate the eyelets, as indicated in Figs. 1 and 3, so as to keep 105 such web normally close to the division 3.

It will be perceived that the supplemental web constituting the division *a* will shield and cover at the back of the belt or carrier the top portions of the hangers which are 110

engaged with eyelets 5, 5, so that with the said portions thus shielded and covered, at the back, and at the front shielded and covered by the division 4, the engaging portions will be completely inclosed.

The invention is not restricted in all cases to embodiment in belts or carriers having the pockets thereof formed with bellows-bottoms.

10 What is claimed as the invention is:—

1. A belt or carrier woven with a plurality of separable divisions, with the eyelets or the like which receive the suspensory devices or hanger-hooks of equipment provided in one of said divisions, and with another of said divisions constituting a covering or guard division at the rear of said eyelets or the like.

2. A belt or carrier woven with a plurality of separable divisions, with the eyelets or the like which receive the suspensory devices or hanger-hooks of equipment provided in an intermediate division, and with

Copies of this patent may be obtained for five cents each, by addressing the "Commissioner of Patents, Washington, D. C."

covering or guard divisions at both sides of the said intermediate division, adapted to cover and shield the tops of the suspensory device or hanger at both the front and the rear of the latter.

3. A woven pocketed carrier having the laterally-extending web thereof divided in thickness laterally alongside the bottom of the pocket into more than two divisions, two thereof respectively constituting direct continuations of the front and back of the pocket and movable therewith apart from each other, and an intermediate division furnished with the eyelet or the like device which receives the suspensory device of other equipment.

In testimony whereof I affix my signature in presence of two witnesses.

CHARLES F. RANDALL.
